WITNESS:

UNITED STATES PATENT OFFICE.

HARRY E. ROSE, OF GEARY, OKLAHOMA.

WRENCH.

1,402,659.

Specification of Letters Patent.

Patented Jan. 3, 1922.

Application filed June 17, 1921. Serial No. 478,386.

To all whom it may concern:

Be it known that I, HARRY E. Rose, a citizen of the United States, residing at Geary, in the county of Blaine and State of Oklahoma, have invented new and useful Improvements in Wrenches, of which the following is a specification.

This invention relates to improvements in wrenches and has for an object the provision of a wrench in which the movable jaw may be quickly operated to provide for rapid adjustment, the adjusting means further providing for adjustment to a small degree.

15 Another object of the invention is the provision of a wrench in which the shank is provided with teeth for engagement with the teeth of the worm carried by the movable jaw, the construction permitting these 20 teeth to be cut on an exceedingly low pitch so as to prevent retrograde creeping of the movable jaw when the wrench is in use.

With the above and other objects in view, the invention further includes the following 25 novel features and details of construction, to be hereinafter more fully described, illustrated in the accompanying drawings and pointed out in the appended claim.

In the drawings:—

30 Figure 1 is a side elevation of a wrench embodying the present invention.

Figure 2 is a similar view showing the movable jaw in longitudinal section.

Figure 3 is a transverse sectional view.

35 Figure 4 is a detail perspective view of the worm actuating spring, showing the assembling pin by dotted lines.

Referring in detail to the drawings, wherein like characters of reference denote 40 corresponding parts, the invention is shown as comprising a shank 10, which carries at one end a stationary jaw 11.

The movable jaw is indicated at 12 and is carried by a sleeve 13 which receives and 45 slides upon the shank 10, the said sleeve being recessed as shown at 14 for the reception of a worm 15. This worm is positioned for engagement with teeth 16 formed transversely of one end of the shank 10, both 50 the teeth 16 and the teeth of the worm 15 being of relatively low pitch and having

one face straight and the opposite face inclined as shown, the inclination being toward the stationary jaw 11.

The worm 15 is rotatably mounted within 55 the recess 14 and by means of a pin 17, one end of which is pointed for engagement with a recess 18 formed in the movable jaw and the opposite end is provided with an enlarged threaded extremity 19 for removable 60 engagement with the teeth 16, the said pin carries a coiled spring 21 whose outer diameter is substantially the same as the bore of the worm. Each end of the spring 21 is formed with a concentrically arranged eye 65 22 which receives the pin 17 so that the latter is centered within the bore of the worm and the worm yieldingly held in engagement with the teeth 16 of the shank.

When it is desired to adjust the wrench 70 to close the jaws, it is only necessary to push the movable jaw toward the stationary jaw, the yieldable engagement of the worm with the teeth 16 permitting the said worm to ride over the said teeth. The movable jaw 75 may be quickly adjusted in a reverse direction by pressing the worm out of engagement with the teeth 16 and holding it in such position until the jaws have been opened the desired distance. After adjustment has been made in this manner, the worm 80 15 may be rotated to secure a more accurate adjustment, the edges of the teeth of the worm being knurled or roughened to facilitate its operation. As the teeth are of a 85 low pitch, the wrench will be held tightly in its adjusted position so that the loss of time and annoyance due to frequent readjustment is obviated.

The invention is susceptible of various 90 changes in its form, proportions and minor details of construction and the right is herein reserved to make such changes as properly fall within the scope of the appended claim.

Having described the invention what is 95 claimed is:—

A wrench comprising a shank, a stationary jaw carried thereby, a movable jaw 100 slidingly mounted upon the shank, a worm carried by the movable jaw for engagement with teeth provided on the shank, said worm

being provided with a relatively large bore, a pin carried by the movable jaw and extending through said bore and a spring located within and having its intermediate 5 convolutions of a relatively large diameter and contacting the walls of the bore and its end convolutions reduced and secured

to the pin, whereby the latter will be normally yieldingly held concentrically of the worm to permit of engagement and disengagement of said worm and the teeth of the shank. 10

In testimony whereof I affix my signature.

HARRY E. ROSE.
